UNITED STATES PATENT OFFICE.

BRIANT SANDO, OF INDIANAPOLIS, INDIANA, ASSIGNOR TO BRIANT SPECIALTY COMPANY, OF INDIANAPOLIS, INDIANA, A CORPORATION.

GAME APPARATUS.

1,384,857.

Specification of Letters Patent. Patented July 19, 1921.

Application filed August 26, 1918. Serial No. 251,451.

To all whom it may concern:

Be it known that I, BRIANT SANDO, a citizen of the United States, residing at Indianapolis, in the county of Marion and 5 State of Indiana, have invented certain new and useful Improvements in Game Apparatus, of which the following is a specification.

This invention relates to a game apparatus comprising an alley or runway for the rolling of balls thereon and a ball receiving and separating means by which the balls are directed into various channels for producing scores.

10 One of the objects of the invention consists in the provision of a game apparatus for promoting healthful physical exercise and mental alertness, and which will be as far as practicable automatic in its operation, 15 thereby disturbing the players as little as possible from pursuing the finer points of the game.

The above objects, and such others as will appear from a reading of the following 20 specification and claims, are attained by means of the construction illustrated in the accompanying drawings, forming a part hereof, in which—

Figure 1 is a perspective view of my improved game apparatus in operation. Fig. 2 is a fragmentary detail vertical sectional view of the discharge end of the runway and ball gatherer and separator. Fig. 3 is an end view of the hopper, on the line 3—3 in Fig. 35 2. Fig. 4 is a horizontal sectional view of the hopper, on the line 4—4 in Fig. 2. Fig. 5 is a horizontal sectional view on the line 5—5 in Fig. 6. Fig. 6 is a vertical sectional view, on the line 6—6 in Fig. 5. Fig. 7 is 40 a vertical sectional view on the line 7—7 in Fig. 5. Fig. 8 is a vertical sectional view, on the line 8—8 in Fig. 5. Fig. 9 is a perspective view of the ball gatherer and separator, showing the construction thereof, 45 with the remaining parts omitted. Fig. 10 is a fragmentary detail perspective view of a part of the actuator mechanism for operating the score tabulating mechanism. Fig. 11 is a top or plan view of the score tabulating mechanism, on an enlarged scale, with the remaining parts of the apparatus omitted. Fig. 12 is a fragmentary detail view of the score tabulating mechanism showing the score indicating blades in their 50 retracted normal position. Fig. 13 is a rear

view of the score tabulating mechanism. Fig. 14 is a vertical sectional view through the score tabulating mechanism, on the lines 14—14 in Fig. 11.

Referring to the drawings, 15 represents 60 the runway upon which balls 16 are rolled, and this runway terminates in a semi-circularly formed deflector 17 for guiding the balls upwardly and away from the runway 15 and into a ball gatherer and separator 18, 65 the latter being supported above runway 15 and between uprights 19 of the frame of the apparatus. In case of a portable apparatus runway 15 may be provided with the supporting legs 20. The player standing at the 70 delivery end of runway 15, as shown in Fig. 1, rolls the balls 16 along the surface of runway 15 with sufficient velocity to cause them to follow the circular formation of deflector 17 and discharge into the mouth of the ball 75 gatherer and separator 18. The ball gatherer and separator comprises a rectangularly shaped box which is arranged transversely of runway 15 and is provided with an inlet ball receiving opening 23 through 80 which the balls pass when discharged from the end of deflector 17. Ball gatherer and separator 18 is divided approximately midway of its height by an inclined division wall 25. About two-thirds of the forward 85 portion of division wall 25 and adjacent to the inlet opening 23 is cut away to form a ball inlet opening 26 which communicates with an inclined floor 27 for directing the balls coming through opening 26 to one end 90 of the separator 18 and out through a discharge opening 28 into a vertically disposed passageway 29 in a hopper 30. Arranged centrally and within the rear half of inclined floor 25 is a ball receiving opening 95 32 of much smaller dimensions than opening 26, and the balls passing through opening 32 pass along an inclined floor 33 and are discharged through an opening 34 into a vertically disposed passageway 35 in hopper 100 30. The separation of the balls discharged from deflector 17 is brought about through the arrangement of openings 26 and 32 and the remaining surface area of inclined floor 25. Thus, if a ball 16 is discharged from deflector 17 upon the surface of inclined floor 25 and beyond the ends of opening 26 they roll by gravity into a receiving trough 38, having an inclined floor 39 to effect the 105 discharge of the balls into a vertically dis- 110

posed ball passageway 40 which directs the balls into return-tube 41 through which the balls are returned to the players' end of the alley. A ball passing along the course here-
 5 tofore described is a blank and will add nothing to the final score of the player, and the possibility of a ball taking the above course is increased by structural arrangement of the apparatus, so that considerable
 10 skill and proficiency is required to so roll each ball along runway 15 as to add to the percentage of player's score. If the player has acquired sufficient skill to roll the balls near the center of the alley he may be able
 15 to effect their discharge into the opening 26 which, as the ball passes downwardly through passageway 29, will actuate certain mechanism for operating the scoring device and thereby increase the percentage of his ultimate score. If the player is able to so roll the balls as to maintain their flight along the longitudinal center of runway 15, the balls may be discharged into the smaller opening 32 so that when passing down-
 20 wardly through passageway 35 will actuate certain mechanism for operating the scoring mechanism and thereby still further increase the percentage of his ultimate score.
 25 It will be readily observed that the differences in areas between the openings 32 and 26, and the remaining surface area of inclined floor 25 are so disproportionate as to render it extremely difficult and requiring much practice and skill to direct the balls
 30 into the central opening 32.

In order to eliminate sounds arising from balls coming into contact with the rear wall of ball gatherer and separator 18 I provide certain means for muffling the sounds which
 40 consists generally of sand filled bags 45 which are suitably arranged to receive the impact of the balls as they are discharged from deflector 17 into separator 18.

It has heretofore been stated that when
 45 the balls are discharged from the inclined floors 27 and 33 the balls pass downwardly through vertically disposed passageways 29 and 35 respectively, and that in their flight they actuate certain means for operating the
 50 score tabulating mechanism, and this mechanism will now be described.

The means for actuating the score tabulating mechanism comprise a pair of U-shaped arms 50 and 51 which have a common bearing upon a shaft 52 arranged in hopper 30. The arms 50 and 51 as shown are of different lengths, thereby causing the free end of arm 50 to move through a greater arc of travel to afford free passage
 55 of a ball 16 through passageway 29 than is necessary for arm 51 to afford free passage of a ball through passageway 35, and this variation in the travel of arms 50 and 51 is important in the operation of the score tab-
 60 ularizing device as will hereinafter more
 65

clearly appear. When a ball is moving downwardly through passageway 29 it depresses lever 50 which in turn depresses a cross-arm 53 arranged in the free end of lever 54 which is pivoted on shaft 52, and as cross-arm 53 is depressed it pulls downwardly on a connecting rod 55 which operates a lever 56 secured to an oscillating shaft 70 mounted between the side members 71 of the score tabulating housing. Shaft 70 carries a pivoted pawl 72 which engages a toothed rack-bar 73 arranged on a horizontally disposed plate 74 having longitudinal movement between side members 71 of the score tabulating housing. A rock-
 75 shaft 75 is mounted in side members 71 and carries a series of loosely mounted indicator blades 57 which contain the numerals for keeping the score. Each indicator blade 57 is provided on its inner and lower edge with an integral foot 57^a and all of the feet stand in the same horizontal plane when the blades 57 occupy normal vertical position, as shown in Fig. 14. A definite and uniform amount is added to the length of each successive foot 57^a from the back to the front of the series of blades 57, and the added length to each foot 57^a coincides to the distance between the teeth on rack-bar 73.
 80 Indicator blades 57 are held in normal vertical position by means of the movable plate 74 and may be released singly or in pairs by imparting the desired amount of longitudinal movement to plate 74. Thus, when a ball is discharged into passageway 35 short 90 lever 51 is depressed, and through cross-arm 53, lever 54, connecting rod 55 and lever 56 oscillating shaft 70 is actuated to move plate 74 the distance of one tooth on rack-bar 73, through the medium of pawl 72, thereby releasing one of the feet 57^a and allowing the connected blade 57 to drop into a horizontal position, as shown by means of the dotted lines in Figs. 13 and 14. The successive blades 57 in the series herein shown are provided with certain numerals as, for instance, the first blade carries the numeral "50"; the next blade "100," and the next "150" and so on throughout the series.
 95 Hence, when plate 74 is moved a distance to 100 free the first blade 57 the numeral "50" will be displayed. Lever 50 is depressed twice the distance traveled by lever 51 by reason of its greater length and incident increase in its range of travel to afford free passage 105 of a ball 16 through passageway 29. This additional movement of lever 50 is sufficient to cause plate 74 to move a distance equal to two teeth of rack-bar 73 which is sufficient movement to release two of the 110 feet 57^a and allowing a corresponding number of blades 57 to drop, thereby displaying an increase of 100 points in the score. As soon as the balls are free of either of the levers 50 and 51 the latter are returned to 115

normal through the medium of springs 58 in Fig. 2. Plate 74 is moved longitudinally away from the feet 57^a in opposition to a spring 76, and to prevent said spring from 5 prematurely retracting said plate 74 when pawl 72 moves backward, I provide a stop-dog 77 which is mounted on a rock-shaft 78 which will be hereinafter described. On each backward stroke pawl 72 is disengaged 10 and held free of rack-bar 73 until it again moves forward, thereby allowing plate 74 to move to normal at the time the resetting mechanism of the score tabulator is actuated for disengaging stop-dog 77 from rack-bar 73. Pawl 72 on its rearward stroke is 15 disengaged from rack-bar 73 by means of a pin 79 contacting the inclined face 80 of stationary block 81 secured to the inner wall of one of the side members 71 of the score 20 tabulating housing. A spring 83 serves to hold pawl 72 in engagement with rack-bar 73 when the pawl is free of stationary block 81. As heretofore stated, there is greater liability on part of the player to roll the balls 25 so that they will be discharged from inclined floor 25 into trough 39 and out of range of either of the openings 26 or 32 so that the balls will pass downwardly through the passageway 40 without adding anything to 30 the score of the player. At the end of a player's turn at play all of the fallen score tabulating blades 57 may be simultaneously raised into their normal vertical position through the medium of a hand-lever 60 located 35 near the players' end of the alley; a connecting rod 61; bell-crank 62; upright connecting rod 63; lever 64; rocker-shaft 65; lever 66 and the U-shaped lifting arms 67. U-shaped lifting arms 67 are mounted 40 on the shaft 75 and when indicator blades 57 drop into horizontal position their rear edges rest against a cross-bar 68 which connects the lifting arms 67 together, and when arms 67 are oscillated on shaft 75 from the 45 players' end of the alley, cross-bar 68 will lift fallen blades 57 into normal vertical position. When the indicator blades 57 reach normal position they are locked by means of the movable plate 74 resting upon the 50 upper edges of feet 57^a. As plate 74 is held, during its intermittent progressive movement in freeing blades 57, in extended position through the medium of stop-dog 77 the latter must first be disengaged from 55 rack-bar 73 before movable plate 74 is free to return to normal position under the influence of spring 76. Stop-dog 77 is disengaged from rack-bar 73 by means of a con-

necting link 85 having an eccentric connection with one of the blade lifting arms 67. 60 When arms 67 have moved blades 57 into normal vertical position, during which movement dog 77 is disengaged from rack-bar 73 through the medium of connecting link 85, and plate 74 moves to its normal 65 position and locks blades 57, dog 77 will immediately reengage rack-bar 73 when lifting arms 67 start to descend, by reason of the freedom of movement afforded said dog through the slotted connection formed by 70 the slot 86 in the end of connecting link 85. In case the game is operated for profit, the movement of hand-lever 60 may be controlled by suitable coin actuated mechanism located in housing 69 near the players' end 75 of the alley.

Having thus fully described my said invention, what I desire to secure by Letters Patent, is—

1. A game apparatus of the character described comprising a runway upon which balls are rolled, a ball receiver and separator communicating with the discharge end of said runway, a floor for dividing said separator into an upper and lower compartment and having a plurality of ball inlet openings, a series of parallel walls for dividing said lower compartment into ball conveying passageways communicating with said ball inlet openings, and a hopper for receiving the balls discharged from the several passageways in the separator and discharging them through a single opening. 80

2. A game apparatus of the character described comprising a runway upon which 95 balls are rolled, a ball receiver and separator communicating with the discharge end of said runway, an inclined floor for dividing said ball separator into an upper and a lower compartment, said floor having a plurality of ball inlet openings, means for conveying the balls discharged from the surface of said inclined floor to one side of the runway, and a plurality of parallel walls for dividing the lower compartment of the separator into longitudinal ball conveying passageways having communication with the ball inlet openings in the inclined floor, the floors in said conveying passageways being inclined for discharging the balls on one 100 side of the runway by gravity. 105

In witness whereof I have hereunto set my hand and seal at Indianapolis, Indiana, this 22nd day of August, A. D. one thousand nine hundred and eighteen.

BRIANT SANDO. [L.S.]
